The ornamental design for an extension handle for body
cleansing apparatus, as shown and described.

DESCRIPTION

FIG. 1 is a front, right side perspective view of an extension
handle for body cleansing apparatus showing our new
design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a front, right side, perspective view of the extension
handle for body cleansing apparatus shown with environ-
mental structure.

In the drawings, the broken lines illustrate portions of the
extension handle for body cleansing apparatus and form no
part of the claimed design. The broken line showing in FIG.
8 is for the purpose of illustrating environmental structure
and forms no part of the claimed design.
